UNITED STATES PATENT OFFICE.

ARTHUR TREVOR DAWSON, GEORGE THOMAS BUCKHAM, AND JAMES FLEMING WHITE,
OF WESTMINSTER, ENGLAND, ASSIGNEES TO VICKERS LIMITED, OF LONDON, ENGLAND, A BRITISH COMPANY.

RECOIL AND RUN-OUT APPARATUS FOR ORDNANCE.

Application filed August 9, 1927, Serial No. 211,736, and in Great Britain January 13, 1927.

This invention relates to ordnance recoil and run-out apparatus employing a pneumatic recuperator the interior of which does not communicate with the interior of the recoil or brake cylinder, that is to say there is no transfer of liquid from the recoil or brake cylinder to the recuperator cylinder during the recoil of the gun.

According to the invention the recuperator cylinder and the recoil or brake cylinder are arranged in line one behind the other and the recoil cylinder or its piston rod, whichever moves relatively to the recuperator cylinder, constitutes or is provided with a ram to effect the compression of the air within the recuperator during the recoil movement of the gun and to effect the run-out movement of the gun under the influence of the compressed air after the recoil movement has been completed. The said recuperator cylinder is preferably arranged behind the recoil cylinder and attached to the gun cradle so that it remains stationary during the recoil and run-out movements of the gun.

The air compressing ram which is arranged in front of and in line with the recuperator cylinder may, in one form, be attached to a crosshead which is connected by longitudinal rods or links to lugs on the breech ring of the gun, suitable guides being provided on the cradle upon which this crosshead slides during the recoil and run-out movements of the gun. Carried within this ram there may be a sleeve which constitutes the recoil cylinder proper and within which the recoil piston is situated, the rod of this piston projecting through the front end of the said recoil cylinder and being attached to a bracket on the cradle. The rear end of the air compressing ram enters the front end of the stationary recuperator cylinder through a suitable gland and the interior of the said ram and of the recoil cylinder is completely shut off from the interior of the recuperator cylinder by means of a wall in the said ram. This wall may have a rearward prolongation forming a cylinder for the reception of a run-out retarding ram projecting rearwardly from the recoil piston.

In a second form the general arrangement of the parts is similar to that above de-

scribed but the recoil cylinder is connected to the cradle, the rear end of the recoil rod is attached to the wall in the air compressing ram, and the retarding ram is connected to the cradle and is disposed in a bore formed in the recoil piston rod.

In a third form the recoil cylinder is connected to the front end of the recuperator cylinder and the air compressing ram is constituted by a rearward hollow extension of the recoil piston rod which extension is connected to a rod passing rearwardly through the rear end wall of the recuperator cylinder where the said rod is attached to the usual lug on the breech ring of the gun. The recoil cylinder and the recuperator cylinder are preferably connected together in a detachable manner to enable access to be had to one or more glands through which the air compressing ram passes. The gland or glands may be carried wholly by the recoil cylinder or wholly by the recuperator cylinder, or one gland may be carried by each cylinder. The arrangement in which the recoil cylinder carries the glands or one of the glands permits the recoil cylinder to be moved away from the recuperator cylinder for the adjustment or renewal of the gland or glands, without the liquid escaping from the recoil cylinder.

In order that the said invention may be clearly understood and readily carried into effect, the same will now be described more fully with reference to the accompanying drawings, in which:

Figure 1 is a vertical longitudinal section of the first form of the invention.

Figure 2 is a transverse section taken approximately on the line 2—2 of Figure 1 and viewed from the right.

Figure 3 is a transverse section taken approximately on the line 3—3 of Figure 1 and viewed from the right.

Figure 4 is a plan of Figure 1.

Figure 5 is a view similar to Figure 1 of the second form of the invention.

Figure 6 is a view similar to Figures 1 and 5 of the third form of the invention, and

Figure 7 is a view similar to the middle part of Figure 6 shewing a modification of certain parts of the latter Figure.

In the various Figures A is part of the

gun, B is part of the cradle, C is the recuperator cylinder, D is the recoil or brake cylinder, D¹ is the recoil or brake piston, D² is the rod of this piston, D³ is the air compressing ram which, during the recoil of the gun, enters the recuperator cylinder to compress the air therein, E is a replenishing tank for supplying the recoil cylinder D with liquid and F is the run-out retarding ram.

Referring to Figures 1 to 4 the air compressing ram D³ is arranged in front of and in line with the recuperator cylinder C and at its front passes through a crosshead D⁴ to which it is attached by means of a nut d⁴, the said ram having a shoulder d³ bearing against the rear part of the crosshead. This crosshead is connected by two longitudinal rods D⁵, D⁶ to lugs A¹, A¹ on the breech ring of the gun and is guided during the recoil and run-out movements of the gun by means of guides B¹, B¹ on the cradle B, upon which guides the crosshead slides. The recoil cylinder D is constituted by a sleeve arranged within and carried by the ram D³ with an annular space between them, this annular space communicating at its front end with the replenishing tank E (formed as part of the crosshead) and communicating at its rear end with the interior of the rear part of the recoil cylinder D by means of holes d, d therein. The rod D² of the recoil piston D¹ projects through a gland d² at the front end of the cylinder D and is attached to a bracket B² on the gun cradle. The cylinder D has longitudinal grooves d^x, d^x of varying cross-sectional area to constitute valve ports for the controlled flow of liquid from one side of the piston D¹ to the other as is, per se, well understood.

The recuperator cylinder C passes through a bracket B³ on the cradle (the aforesaid rods D⁵, D⁶ passing through the side portions of this bracket) and is attached by means of a nut b³, the front end of the said cylinder having a shoulder C¹ bearing against the front surface of the said bracket. The front end of the recuperator cylinder C has a gland C² through which the air compressing ram D³ enters the said cylinder and the interior of this cylinder is completely shut off from the interior of the said ram and of the recoil cylinder D by means of a wall D⁶ which is made integral with the ram D³ and has a rearward prolongation d⁶ (closed at its rear end by a screwed plug d^{6x}) forming a cylinder for the reception of the aforesaid run-out retarding ram F which projects rearwardly from the piston D¹ as is well understood. The run-out control effected by this retarding ram may be varied in accordance with the angle of elevation at which the gun is firing, by means of a tapered plug valve F¹ disposed in a passage F² leading from the rear end of the recoil

cylinder to the retarding ram cylinder d⁶. This plug valve is formed on the rear end of a rod F³ which passes centrally through the recoil piston rod D² and has at its front part a screw-threaded portion f³ engaging with screw threads in the piston rod so that by angularly adjusting the rod F³ the plug valve F¹ can be moved into or out of the passage F² as required in order to vary the effective area of the passage. The angular adjustment of the rod F³ is preferably effected automatically during the elevation of the gun by suitable means such as those well known for angularly adjusting a part appertaining to the valve port of the recoil piston.

Referring to Figure 5, the recoil or brake cylinder D is connected to a block D^x which is attached to the bracket B² on the gun cradle B and carries the replenishing tank E, and the rear end of the recoil piston rod D² is connected by screw threads to the aforesaid wall D⁶ in the ram D³. The retarding ram F is connected to or made integral with the said block D^x and is disposed in an axial bore in the piston rod D², the tapered plug valve F¹ and its operating rod F³ are carried by the block D^x and the grooves for controlling the flow of liquid from one side of the recoil piston D¹ to the other are formed in the outer surface of the retarding ram F. The air compressing ram D³ is connected to a crosshead D⁴ mounted to slide on guides B¹ on the cradle B and connected by rods to lugs on the gun as in Figures 1 to 4. In other material respects the construction of recoil and run-out apparatus shewn by Figure 5 is similar to that shewn by Figures 1 to 4 and the same reference letters are used to indicate similar parts. It will be observed that in the construction according to Figure 5 the recoil and run-out apparatus is situated below the gun instead of above it as in Figures 1 to 4.

In the construction shewn by Figure 6 the recoil cylinder D is connected to the front end of the recuperator cylinder C which is connected to a bracket B³ on the gun cradle B as in the previous figures and the air compressing ram D³ is constituted by a hollow rearward extension of the recoil piston rod D². This hollow ram D³ is connected to a rod D^{3x} passing rearwardly through a gland C² in the rear end of the recuperator cylinder C and the projecting part of this rod is attached to the usual lug A¹ on the breech ring of the gun. The rear part of the hollow ram D³ has small holes d^{3x}, d^{3x} which establish communication between the interior of this ram and the interior of the recuperator cylinder C. The replenishing tank E is carried by the recoil cylinder D and the arrangement of the retarding ram F and its associated parts is substantially the same as that described with reference to

Figure 5. The above mentioned connection between the recoil cylinder D and the recuperator cylinder C is of a detachable character (preferably by means of set screws one of which is shewn at C^{1x}) to enable access to be had to the glands C² through which the aforesaid hollow air compressing ram D³ passes and which are shewn as being carried by the recuperator cylinder C but may be carried by the recoil cylinder D. It will be seen that in this construction the complete recoil and run-out apparatus constitutes one unit which can be arranged either above or below the gun as required and that only one connection to the gun is required viz, the connection between the aforesaid rearwardly extending rod D^{3x} and the lug A¹ on the breech ring of the gun.

Figure 7 shows a modified arrangement of the glands C² of Figure 6. In this modified arrangement there are two separate glands one, C², carried by the recuperator cylinder C and another, C^{2x}, carried by the recoil cylinder D. This arrangement enables the recoil cylinder D to be moved away from the recuperator cylinder C, for the adjustment or renewal of one or both of the glands C², C^{2x}, without the liquid escaping from the recoil cylinder D. A similar result is obtained when the glands are carried wholly by the recoil cylinder as mentioned above.

What we claim and desire to secure by Letters Patent of the United States, is:—

1. In ordnance recoil and run-out apparatus, the combination with the recoil or brake cylinder and the recoil or brake piston forming the elements of the recoil apparatus, one of these elements being connected to the gun and the other to the gun cradle, of a pneumatic recuperator cylinder which is arranged in line with the recoil or brake cylinder and the interior of which does not communicate with the interior of the latter cylinder, and a ram on the recoil apparatus element that moves relatively to said recuperator cylinder, said ram effecting the compression of the air within said recuperator cylinder during the recoil movement of the gun and effecting the run-out movement of the gun under the influence of the compressed air after the recoil movement has been completed.

2. In ordnance recoil and run-out apparatus, the combination with the recoil or brake cylinder and the recoil or brake piston forming the elements of the recoil apparatus, one of these elements being connected to the gun and the other to the gun cradle, of a pneumatic recuperator cylinder which is attached to the gun cradle in line with the recoil or brake cylinder and the interior of which does not communicate with the interior of the latter cylinder, and a ram on the recoil apparatus element that moves relatively

to said recuperator cylinder, said ram effecting the compression of the air within said recuperator cylinder during the recoil movement of the gun and effecting the run-out movement of the gun under the influence of the compressed air after the recoil movement has been completed.

3. In ordnance recoil and run-out apparatus, the combination with the recoil or brake cylinder, means for connecting said cylinder to the gun cradle, a recoil or brake piston working in said cylinder, a pneumatic recuperator cylinder which is arranged in line with said recoil or brake cylinder and the interior of which does not communicate with the interior of the latter cylinder, means for connecting said recuperator cylinder to the gun cradle, a ram for effecting the compression of the air within said recuperator cylinder during the recoil movement of the gun and effecting the run-out movement of the gun under the influence of the compressed air after the recoil movement has been completed, means for connecting said ram to the gun so as to move therewith and means for connecting the recoil or brake piston to said ram.

4. In ordnance recoil and run-out apparatus, the combination with the recoil or brake cylinder, means for connecting said cylinder to the gun cradle, a recoil or brake piston working in said cylinder, a pneumatic recuperator cylinder which is arranged behind and in line with said recoil or brake cylinder and the interior of which does not communicate with the interior of the latter cylinder, means for connecting said recuperator cylinder to the gun cradle, a ram for effecting the compression of the air within said recuperator cylinder during the recoil movement of the gun and effecting the run-out movement of the gun under the influence of the compressed air after the recoil movement has been completed, means for connecting said ram to the gun so as to move therewith, and means for connecting the recoil or brake piston to said ram.

5. In ordnance recoil and run-out apparatus, the combination with the recoil or brake cylinder and the piston working therein, of a pneumatic recuperator cylinder the interior of which does not communicate with the interior of said recoil or brake cylinder, means for attaching said cylinders together with the recuperator cylinder in front of and in line with the other cylinder, means for connecting one of said cylinders to the gun cradle, a rearward extension of the rod of said recoil or brake piston, said rearward extension constituting a ram for effecting the compression of the air within said recuperator cylinder during the recoil movement of the gun, and effecting the run-out movement of the gun under the influence of the compressed air after the recoil movement.

has been completed, a rod connected to said ram and passing rearwardly through the rear end of said recuperator cylinder and means for connecting said rod to the gun 5 so as to move therewith.

6. In ordnance recoil and run-out apparatus, the combination with the recoil or brake cylinder and the piston working therein, of a pneumatic recuperator cylinder the interior of which does not communicate with the interior of said recoil or brake cylinder, means for detachably connecting said cylinders together with the recuperator cylinder in front of and in line with the other cylinder, means for connecting one of said cylinders to the gun cradle, a rearward extension of the rod of said recoil or brake piston, said rearward extension constituting a ram for effecting the compression of the air within 10 said recuperator cylinder during the recoil movement of the gun and effecting the run-out movement of the gun under the influence of the compressed air after the recoil move- 15

ment has been completed, a rod connected to said ram and passing rearwardly through the rear end of said recuperator cylinder and means for connecting said rod to the gun so as to move therewith. 25

7. In ordnance recoil and run-out apparatus, the combination with the elements 30 claimed in claim 6, of at least one gland through which the ram passes, this gland being exposed when the cylinders are separated from each other.

8. In ordnance recoil and run-out apparatus, the combination with the elements 35 claimed in claim 6, of a gland carried by the recoil or brake cylinder for the ram and another gland carried by the recuperator cylinder for said ram, these glands being exposed when the cylinders are separated from each other. 40
